J. S. CLARKE

FOOTWEAR

Filed July 5, 1921

FIG.1.

FIG.2.

FIG.3.

FIG.4.

FIG.5.

Inventor,
James S. Clarke
by Herbert W. Jenner,
Attorney.

UNITED STATES PATENT OFFICE.

JAMES SEALY CLARKE, OF WESTMINSTER, LONDON, ENGLAND, ASSIGNOR TO WOOD-MILNE, LIMITED, OF WESTMINSTER, LONDON, ENGLAND.

FOOTWEAR.

Application filed July 5, 1921. Serial No. 482,375.

To all whom it may concern:

Be it known that I, JAMES SEALY CLARKE, a subject of the King of Great Britain and Ireland, residing at Westminster, London, England, have invented certain new and useful Improvements in and Relating to Footwear; and I do hereby declare the following to be a full, clear, and exact description of the invention, such as will enable others skilled in the art to which it appertains to make and use the same.

This invention has reference to soles and heels or sole or heel pads formed of india rubber or the like resilient material, for attachment to boots and shoes. The object of the invention is to provide an improved construction of such soles and heels or sole or heel pads of great lightness, and presenting numerous advantages over existing protective soles and heels of the kind in question, in that uniform wear is ensured by the provision of a tread surface of ample area and liability of slipping on wet roads is reduced by means that also serve to augment the cushioning effect and thereby conduce to ease in walking.

As heretofore usual the improved sole or heel, or complete sole and heel in one piece, or sole or heel pad or tip, hereinafter referred to as sole, is adapted to be affixed to the bottom of a boot or shoe by a suitable adhesive, or by screws or nails the heads of which are sunk, or by sewing, or by any combination thereof. If nails or screws are employed the holes therefor may in the known and usual manner be fitted with metal strengthening plates or washers.

According to the invention the improved sole comprises a base or foundation from which projects a tread or thickened portion formed with recesses in which are arranged projections of relatively small cross section and of any desired shape such for example as circular, oval or polygonal, the construction and arrangement being such that in use the weight and wear is taken by the tread or thickened portions the projections of small cross section being free to expand in the recesses when subjected to pressure and also free to assume canted or inclined positions calculated to resist any tendency of the sole or heel to slip when in use and gener-

ally to augment the non-slipping properties of the sole.

In order to allow the escape of air that otherwise might be trapped in the recesses when the sole is in use, and consequently to avoid the sucking action and unpleasant squelching noise that might then obtain, the surface of the tread or thickened portions, or some of them, is formed with grooves or serrations that extend from the recesses to the outer edges of the said tread or thickened portions.

For the purpose of increasing the life of a protective sole or sole pad formed of india rubber or the like the toe end thereof is thickened towards the end so as to provide an increased thickness of material at the part most subject to wear.

With advantage the before mentioned projections of relatively small cross section are raised relatively to the thickened or tread portions, that is to say they project slightly beyond the same so that when the sole or heel is in use the projections first meet the ground and are compressed before the weight and wear is received by the thickened or tread portions of the sole.

Preferably the said projections are of circular cross section and the recesses in which they are arranged are of circular shape and concentric to the said projections.

Fig. 1 of the accompanying drawings shows in plan one formation of a rubber sole embodying the invention.

Fig. 2 is a longitudinal section corresponding to the line 2, 2 of Fig. 1.

Fig. 3 is a part plan of a rubber sole with a thickened toe portion.

Fig. 4 is a section corresponding to the line 4, 4 of Fig. 3, and

Fig. 5 is a side elevation of the toe end of a boot to which a rubber sole of the kind shown in Figs. 3 and 4 is fitted.

The sole illustrated in Figs. 1 and 2 comprises a base or foundation 1 the marginal portion of which is tapered off to a thin or feather edge in known manner to facilitate the secure cementing of the sole edges to a boot or shoe and to prevent any possibility of such edges becoming loose during wear. Formed integrally with such foundation are thickened or tread portions 2 hav-

ing recesses 3 therein. In each recess 3 is a projection 4 also formed integrally with the foundation 1 and extending slightly beyond the surface of the tread portions 2. In the 5 example shown each projection 4 is of circular cross section and is arranged at the centre of the corresponding recess 3 which is of circular shape. To prevent air being trapped in the recesses 3 the surface of the 10 raised or tread portions 2, except the surface of the raised or tread portion at the toe end, is formed with a plurality of grooves 5 communicating with the recesses 3 and extending therefrom to the outer edges of the 15 raised or tread portions 2. The grooves 5 also augment the non-slipping character of the sole.

Near the waist end the sole may be formed with a shallow recess 6 of circular or other 20 shape in which may be moulded the trade mark or name of the manufacturer, and a recess 7 of rectangular or other shape in which may be moulded the size of the sole and any other particulars desired.

25 Figs. 3, 4 and 5 illustrate how the toe end of a rubber sole may according to this invention be thickened to increase the life of the sole. As will be seen from Fig. 5, a boot normally curves upwardly towards the toe end 20 and by thickening the toe end of the protective rubber sole towards the end not only is the life of the protective sole increased by the extra thickness of material at such part but there is provided a more 25 level tread that conduces to easy walking. As seen particularly in Fig. 4, the thickened toe end 8 does not terminate abruptly but in a gentle curve 9 that blends into the feather edge 10.

30 It will be understood that without departure from the invention considerable modifications in details may be made, for example the flexible projections are not necessarily circular in cross section, neither 45 is it essential that such projections should project beyond the tread surface; moreover,

the number and arrangement of the projections and corresponding recesses can be varied as desired.

What I claim as my invention and desire 50 to secure by Letters Patent is:—

1. A rubber tread plate for footwear having a tread or weight bearing surface formed with a series of recesses distributed throughout its area in each of which is arranged a plain pensile stud of small cross section raised relatively to the wearing surface of the plate, each such plain pensile stud being adapted to give under pressure and to expand and cant or assume an inclined position within its corresponding recess. 55

2. A rubber tread plate for footwear having a tread or weight bearing surface formed with a series of circular recesses distributed throughout its area in each of which is arranged a plain pensile stud of small circular cross section raised relatively to the wearing surface of the plate, each such plain pensile stud being adapted to give under pressure and to expand and cant or assume an inclined position within its corresponding circular recess. 60

3. A rubber tread plate for footwear having a tread or weight bearing surface formed with a series of circular recesses distributed 65 throughout its area in each of which is arranged a plain pensile stud of small circular cross section raised relatively to the wearing surface of the plate, each such plain pensile stud being adapted to give under pressure 70 and to expand and cant or assume an inclined position within its corresponding circular recess, and air escape grooves extending between the several circular recesses and to the sides of the plate. 80

85 In testimony whereof I affix my signature in presence of two witnesses.

JAMES SEALY CLARKE.
